SLOTTED DISPENSER PARTITION
FOR CARRYOUT

Kenneth S. Kagen, York, and Franklin A. Ness, West Manchester Township, York County, Pa., assignors to Keystone Paper Box Company, York, Pa., a corporation of Pennsylvania

Filed Feb. 24, 1960, Ser. No. 10,716
4 Claims. (Cl. 229—15)

This invention relates to an article carrier and, more particularly, to article carriers formed from the individual partition members of a nested partition.

In various roadside stands vending ice cream cones and like articles, when several such cones are sold to an individual for transporting to an automobile, some means must be provided to enable the purchaser to carry the several cones. We have now provided a method of converting the assembled portions of a nested partition into such article carriers.

Some cones for receiving ice cream are sold in an elongated box, having a nested partition therein, dividing the box into four sections for receiving the cones. The nested partitions serve to maintain the columns of cones spaced from each other and thereby prevent damage to the cones. Ordinarily, the nested partitions are disposed of when the box of cones is empty. However, by use of the herein disclosed invention, each portion of the partition is adapted for folding into an article carrier.

It is an object of the invention therefor to provide for a nested partition wherein each member of same is suitable for folding into an article carrier after its primary use as a partition has been accomplished.

A further object of the invention is to provide an article carrier which is of light, yet rugged construction, easily assembled, and well adapted for its intended purpose.

The invention consists of the novel constructions, arrangements and devices to be hereinafter described and claimed for carrying out the above-stated objects and such other objects as will appear from the following description of a preferred embodiment of the invention described with reference to the accompanying drawings, in which:

FIG. 1 is a perspective of a typical nested partition showing the receiving box in dashed outline therearound;

FIG. 2 is a plan view of a partition showing the location of the various crease lines and scored portions necessary for connecting the same into an article carrier and prior to its being assembled; and

FIG. 3 is a view in perspective of a partition assembled to form an article carrier.

Like numerals refer to like parts throughout the several views.

Turning now to the drawings, FIG. 1 discloses a pair of partition members 10, suitably nested together to form a nested partition. The partitions are identical and are formed with a longitudinal slit 11 along approximately 50% of the length, each said slit acting to accommodate the unslotted portion of the opposite partition member. A box B is shown to illustrate the manner in which the nested partition functions.

Turning now to FIG. 2, a partition 10' is disclosed which has been suitably creased and scored so that it may be formed into an article carrier. Partition 10' is provided with a crosswise crease 12, dividing the partition into an article carrying portion 13 and a supporting portion 14. Article carrying portion 13 is provided with a crosswise crease 15 parallel to crease 12. Crease 15 divides the article carrying portion into a top section 16 and a first side section 17. A scored knock-out portion

2

18 is provided, which, when removed, defines a tab receiving groove 19. A plurality of scored knock-out portions 20 are provided in top section 16, which, when removed, define article receiving apertures 21. Knock-out portions 20 would be of a size sufficient to accommodate whatever article it is desired to support therein. It will be apparent that the number of knock-out portions 20 may vary as circumstances dictate.

Inspection of FIG. 2 reveals that longitudinal slit 11 divides the supporting portion 14 in two. A pair of crosswise slits 22 and 23 are provided extending from slit 11 into each side of supporting portion 14. Each side of supporting portion 14 is further provided with oppositely directed transverse creases 24 and 25. Similar transverse creases 26 and 27 are provided adjacent ends 28 and 29 of supporting portion 14, serving to define a pair of tabs 30 and 31. Those parts of supporting portion 14 lying between crease 12 on the one hand and 24 and 25 on the other, define a bottom section 32, while those parts of supporting portion 14 lying between creases 24 and 25 on the one side and creases 26 and 27 on the other, form a second side section 33.

Turning now to FIG. 3, a method of assembling partition 10' into an article carrier will be described. The two sides of supporting portion 14 are interlocked by way of slits 22 and 23. Creases 24 and 25 are so situated that when the two sides of supporting portion 14 are so interlocked, the creases coincide with each other and, in effect, form one crease parallel to crease 12. Similarly, creases 26 and 27 coincide with each other, when the two sides of supporting portion 14 are interlocked by way of slits 22 and 23, permitting tabs 30 and 31 to coincide.

The partition is folded along crease lines 15, 12 and 24—25. Tabs 30 and 31, which coincide, as aforesaid, when the two sides of supporting portion 14 are interlocked, are inserted upwardly through groove 19 from which, prior to this time, the knock-out portions 18 had been removed. Tabs 30 and 31 are then oppositely folded to form a lock, maintaining the carrier in assembled relation.

Knock-out portions 20 are removed and the carrier is now ready to receive the various articles to be transported.

It will be apparent that partitions 10 will vary both in length and width, depending on the size of the box B into which they are to be inserted.

It will also be apparent that the height of the carrier, as defined by side sections 17 and 33, may vary, depending on the height of the article to be transported. Further, the number and size of knock-out portions 20 may be varied at will, depending on the size of the partitions and of the articles to be received therein. In preparing the partition with the various crease lines, it is only necessary that top section 16 and bottom section 32 be of the same length. Similarly, the two side portions 17 and 33 must be of the same length.

We wish it to be understood that our invention is not to be limited to the specific construction and arrangements shown and described, except only insofar as the claims may be so limited, as it will be apparent to those skilled in the art that changes may be made without departing from the principles of the invention.

We claim as our invention:

1. An article carrier comprising an elongated blank having an intermediate crosswise crease therein dividing the blank onto an article carrying portion and a supporting portion, said article carrying portion having a crosswise crease therein parallel to said aforementioned crease defining a top and first side section, said supporting portion having a longitudinal slit therein dividing said supporting portion into two sides, said supporting portion further having a crosswise slit therein intermediate the

ends of said longitudinal slit and extending from said longitudinal slit into each side of said supporting portion whereby said two sides of said supporting portion may be interlocked, each said side of said supporting portion being further provided with an oppositely disposed non-parallel transverse crease so situated that when the two sides of said supporting portion are interlocked said transverse creases coincide with each other and are parallel to said aforementioned creases for dividing said supporting portion into a bottom and second side section, and means for maintaining said second side section in assembled relation with said top section when said blank is folded to form said article carrier.

2. The article carrier as set out in claim 1, further including a plurality of knock-out portions in said article carrying portion defining article receiving apertures.

3. The article carrier as set out in claim 1, wherein said means for maintaining said second side section in assembled relation with said top section comprises a tab on said second side section and said top section having a tab receiving aperture therein, said tab receiving aperture being defined by a knockout portion.

4. In a partition, comprising an elongated blank having a longitudinal slit therein along approximately half the length thereof providing two sides for adapting said partition for nesting with a like partition, the improvement

comprising an intermediate crosswise crease therein dividing said partition into an article carrying portion and a slotted supporting portion, said article carrying portion having a crosswise crease therein parallel to said aforementioned crease defining a top and first side section, means for interlocking said two sides of said supporting portion comprising a crosswise slit intermediate the ends of said longitudinal slit and extending from said longitudinal slit into each side of said supporting portion, each 5 said side of said supporting portion being further provided with a transverse crease for dividing said supporting portion into a bottom and second side section, and means for maintaining said second side section in assembled relation with said top section when said partition is folded to form said article carrier.
